LIQUID SEALED PUMP

Harry E. La Bour, Elkhart, Ind.

Application April 17, 1942, Serial No. 439,361

22 Claims.

(Cl. 103—103)

My invention relates to centrifugal pumps and more particularly to self-priming pumps.

The chief object of the invention is to provide an improved method of and means for liquid sealing the shaft of a pump.

Another object of the invention is to provide means for insuring segregation of the bearings from the sealing liquid. A further object is to provide a seal against the escape of fumes or vapor from the pump.

A further object is to provide an improved mounting for the pump. A further object of the invention is to provide a design having particular advantages for production in acid resisting materials.

A further object is to provide an improved restriction against too rapid backflow.

A further object is to provide a self-priming centrifugal pump of a design which may advantageously employ a liquid seal of my invention and embody other and incidental improvements.

Other objects will appear from the following detailed description and drawings, disclosing a specific embodiment of my invention. The specific embodiment herein disclosed is a pump, particularly designed for acid service, but the invention is not to be limited thereto, as the invention may be used in pumps for a wide variety of service.

The problem of liquid sealing a pump shaft for the present class of service has already been solved by my prior invention disclosed and claimed in my prior Patent No. 2,250,714. The method therein employed is to utilize liquid being pumped to fill an annular cylindrical gap between the shaft and a surrounding seal sleeve, the outer end of which is open to atmosphere, and the inner end into the intake. The method is particularly advantageous during priming in that the liquid is circulated through the sleeve under no greater pressure difference than that between atmosphere and the prevailing suction and the liquid returns into the priming intake. Upon the pump attaining discharge pressure, the aforesaid circulation occurs under the full differential between discharge and suction and the outflow under the differential between discharge pressure and atmosphere. While the aforesaid prior pump eliminated the rubbing friction of solid material seals previously found necessary and constituted a pronounced improvement in the art, the flow of sealing liquid both internally and externally gave opportunity for increase in overall efficiency. Also in some special circum-

stances, such as abrasive solids in the liquid being pumped, there was a tendency for the sleeve to wear and thereby allow increase in the flow of the sealing liquid.

5 The provision of a liquid seal for a rotating shaft has long engaged the attention of engineers and inventors. A method which early attracted the attention of designers of steam turbines was the concept of a rotating ring of liquid embracing the periphery and margins of an intervening flange. See United States Patents Nos. 773,297 and 813,723, in which mercury was used as the sealing liquid. The concept here was to produce a kinetic manometer in which, under 10 the centrifugal or inertia effect, the rotating liquid would provide a pressure many times that of gravity. A simple bell dipping into a ring of liquid gives only the static manometer effect, and hence is useful only for very low pressure differences. See United States Patent No. 15 991,225. In some cases the two principles of the static and kinetic manometer are combined as in United States Patent No. 1,213,494.

20 McGee Patent No. 1,949,428 proposes to provide a horizontal pump with sealing channels in which rotating discs with paddles on both sides serve to whirl the sealing liquid. Aside from the fact that a seal of the character there disclosed cannot be made to sustain full atmospheric pressure without going to excessive diameters or excessive speeds, the complicate priming mechanism required is out of the question. Also, such an arrangement is wholly unsuited to acid service. In a modified form (United States 25 Patent No. 1,949,429) the same inventor proposes to carry the whirling ring of liquid in a rotating channel ring. The unsuitability of this form of device for a self-priming pump, and also for a pump in acid service, will at once be apparent aside from the impossibility of securing sufficient manometer effect without going to excessive diameters or speeds. The backward suction occurring in a self-priming pump when the impeller slows down to a stop would empty 30 the seal of such a construction and render the pump incapable of developing its suction on again starting up.

35 Bischof (United States Patent No. 1,421,389) proposes the use of a chamber below the impeller to trap priming liquid. The trap chamber is intended to provide also a whirling channel member cooperating with a stationary disc. The arrangement presents the advantage of trapping liquid for priming the seal, but the seal is not efficacious, as I have found by trial. Excessive

diameters or speeds would be required, and no provision can be made for eliminating entrained abrasive solids.

According to the present invention, the principle of the rotating ring of sealing liquid is modified by constituting the one side of the ring an active pumping element and constituting the other side a sealing space or gap in which a reduced or even minimum pumping effect is produced. In the preferred embodiment, I combine the static standpipe with the sealing ring of liquid. The chief service of the static standpipe is to conserve priming liquid during priming or for priming service.

This form of seal peculiarly cooperates with the form of self-priming pump of my invention, the principle of which pump is disclosed in my prior United States Patent No. 1,578,236, because during priming relatively little priming liquid reaches the central part of the impeller. Hence, although the seal itself in the preferred form constitutes a small pump, that pump is robbed of liquid during the priming operation, and the practical effect is that not much, if any, liquid is discharged through the seal.

Upon a vacuum or reduced pressure being attained in the pump, the differential of pressure so produced tends to hold back or oppose the discharge of sealing liquid. The seal may be laid out to produce the amount of discharge desired to keep entrained solids flushed out, or it may be laid out to stop the flow of liquid altogether when a certain degree of subatmospheric pressure is produced in the pump. A pump and seal structure of unusually high efficiency and of marked effectiveness is produced.

Liquid seals of the prior art to which I have above referred are all designed to pass no fluid while they are in operation. The seal of my invention in its preferred form is designed to pass liquid while in operation, but to be tight against the entry of air into the pump. This passing of liquid is permissible because a self-priming pump can always be set above the source of liquid to be pumped and the outflowing seal liquid returned by gravity to the source. If the pump is arranged to withdraw fluid from a source which is at subatmospheric pressure, then the pressure difference may be employed to return the sealing liquid to the source. On stopping of the pump the outflow of sealing liquid ceases.

The pump impeller, or any other driven device, might lie below the seal. The seal may be employed for a shaft which does not drive a pump impeller. However, since the seal is intended to be able to pass liquid and to remain airtight, liquid for that purpose should be provided. In the preferred form of my invention, the liquid which is being pumped, or being circulated during priming, serves the function of supplying the liquid for the seal.

Where the pressure difference is limited, as in the case of the suction of a self-priming pump, the pumping side of the seal needs to be designed to give only sufficient discharge pressure to balance the possible pressure difference. It is not necessary that liquid be passed through the seal when the pressure difference upon the seal is great enough to equal the pumping pressure. The seal may be designed to sustain any particular value of pressure difference greater or less than one atmosphere, but it is a virtue of the present design that the pressure difference on the seal in the present pump is not greater than one atmosphere as a maximum.

The so-called sealing disk does not need to be a disk. A cylinder or a sphere, or in fact almost any solid having its surface generated by rotation of a loop about an axis would do, the channel in each case conforming to the shape of the stationary body or vice versa. A disk is economical of space and material and hence is preferable.

Now in order to acquaint those skilled in the art with the manner of constructing and operating a device embodying my invention, I shall describe, in connection with the accompanying drawings, a specific and preferred embodiment of my invention and the several improvements which I have made.

In the drawings:

Figure 1 is a vertical longitudinal section of a vertical self-priming centrifugal pump of my invention, taken on line 1—1 of Figure 2;

Figure 2 is a horizontal cross section taken on the line 2—2 of Figure 1;

Figure 3 is a fragmentary section, taken through the auxiliary throat on the line 3—3 of Figure 2;

Figure 4 is a fragmentary cross section taken across the auxiliary throat on the line 4—4 of Figure 2;

Figure 5 is a vertical cross section through the top half of the rotor, showing the blades of the pump impeller and the blades of the asymmetrical seal;

Figure 6 is a top plan view with a part broken away, as indicated on the line 6—6 of Figure 5, to reveal the main impeller blades in plan and likewise the impeller blades of the seal in plan;

Figure 7 is a fragmentary side elevation from the left of Figure 1, showing the cover for the screen and backflow retarding valve;

Figure 8 is a bottom plan view with parts broken away, showing the drain closure which may be opened to drain the seal and connected passageways; and

Figure 9 is a fragmentary sectional view through a modified form of seal showing full length blades on the suction side and a non-bladed gap at the outer margin of the other side with radially shorter blades on the latter side to control the rate of passing liquid through the seal.

The pump illustrated herein comprises as the main structural parts the pump body casting 1, the lower body casting 2, resting on the base or stand 3, the bearing barrel 4, the sealing sleeve and disk member 5, the rotor 6 and rotor shaft designated collectively as 7.

The main body casting 1 comprises three concentric cylindrical walls, namely, the outer wall 8, which defines the outer extent of the trap chamber 9, the intermediate wall 10 which defines the outer extent of the intake trap 12, and the inner concentric wall or sleeve 13 which mounts the sealing sleeve and disk member 5. These three walls, 8, 10 and 13, are joined at their upper ends by the top wall 14 which in this specific form is substantially horizontal. An intake connection 15 at the right is formed integrally with the body casting 1, and it consists of a short tubular neck terminating in the flange 16 by which the intake connection 15 may be joined to a suction pipe or hose. This intake connection 15 has an intake passageway 17 extending therethrough and communicating with intake trap 12. The said intake passageway 17 extends substantially over the top of the separator chamber, and opens downwardly as at

18 into the said intake trap at one side of a hollow boss or neck 20 which is integral with and extends upwardly from the top wall 14 in substantially concentric relation to the body sleeve 13 and the concentric walls 10 and 8. The passageway 17 is enlarged as at 22 to make provision for receiving the screen plate 23 shown in section in Figure 2. This screen plate sits in a bottom groove 24 in the wall of the intake passageway 17, and projects upwardly out of the opening 25 formed in the said intake connection 15. A domed closure or cover member 26 has a groove or notch at each side for holding the screen plate in position. The screen plate or strainer 23 lies transversely across the intake passageway 17 and its purpose is to screen out or strain out coarse impurities which might accidentally get into the intake of the pump. The present pump is designed primarily for chemical service, but the invention is not to be limited to that particular service. It is to be understood that the present preferred embodiment is not expected to handle liquid with entrained miscellaneous solids. The pump will satisfactorily serve for liquid containing abrasives in the nature of fine liquid borne crystals or the like. The strainer 23 is not intended to be any more than a safety device for preventing an object from being accidentally passed into the pump which might injure the same. A swinging flap valve 28 which has hinge pins or trunnions 29 at each upper corner thereof is suspended in pockets or recesses 30 at the sides of and below the opening 25. This valve 28 is not intended to make a tight closure, but to retard backflow and to allow air to pass up and over the valve and to break the vacuum in the suction line when the impeller slows down to a stop. The cover member 26 has ears 29, 29 overlying the ears 30, 30 formed on the intake connection 15, the said ears and mating flanges being provided with an interposed gasket. The ears 29, 30 are clamped together by bolts 33, 33 and nuts 34, 34 which are threaded upon the shanks of the bolts. The upper ends of the bolts are provided with threads as indicated at 35, 35, and clamping nuts 36, 36 press the central boss 38 of a clamping yoke 37 upon the top of the dome shaped cover 26 to provide additional pressure between the bolts to insure a tight seal of the cover over the opening.

A discharge connection 40 provides a passageway 42 communicating with the top of the separator chamber 9, and through this discharge connection 42, air is driven during priming, and liquid during pumping. The three concentric walls 8, 10 and 13 are, at their lower ends, machined off in substantially the same transverse plane. The outer wall 8 is provided at its lower peripheral margin with a clamping flange 43, which mates with a corresponding clamping flange 44 on the bottom casting 2, the two parts being piloted together by pilot projection 45 and pilot recess 46 with an interposed gasket 47. The two flanges 43 and 44 are held together by clamping rings 48 and 49. The lower ring 49 is preferably a continuous ring, and the upper ring 48 is preferably split into two parts, as indicated at 49 in Figure 2. Clamping bolts pass through the two rings and clamp the two pump castings 1 and 2 together in sealed relation. The inside surface of the outer wall 8 has an inwardly extending flange 52 which tends to confine the whirling liquid of the priming charge during priming. The outer surface of the rim of the

trap wall 10 is machined to provide a cylindrical engaging surface for the flange 54 of the top side plate member 55. The side plate member 55 has a central opening 56 therethrough which leads from the bottom of the trap into the eye of the impeller 57 which is formed on the top of the rotor 6. The impeller 57 comprises open blades 58 (see Figures 5 and 6), eight straight blades in this specific instance, formed integral at their lower sides with an annular disk 59 which forms the top half of the rotor 6. The bottom casting 2 has an outer cylindrical wall 60 of substantially the same diameter as the wall 8 of the top casting 1, and it has a bottom wall 62 which is depressed at the center to provide the bottom side plate 63. An annular cylindrical wall 64 integral with the side plate 63 closely embraces the rotor 6.

The bottom wall 63 and the peripheral cylindrical wall 64 define a cylindrical recess which constitutes the rotor chamber 65 which is most clearly indicated in Figures 2 and 4. The top part of the rotor chamber as defined between the top side plate member 55 and the disk 59 constitute the impeller chamber, that is, the chamber within which the main pumping effort of the pump is developed. The bottom wall 63 has an apertured boss 66 which is closed by a hollow threaded plug 67, the flange 68 of which cooperates with the end of the boss 66 through the medium of a suitable gasket to form a tight closure. The cylindrical wall 64 is provided at the level of the blades 58, 58 with appropriate throating to constitute the pump a self-priming pump of the so-called hydraulic balance type, that is, the type which during priming permits the reentry of priming liquid into the periphery of the blades for the purpose of forming a mixture of liquid and gas and discharging the said mixture into the separator 9. In the separator, the gas rises to the outlet 42 due both to gravity separation and whirling or centrifugal separation which is fostered by the design of the present pump.

The top side plate member 55 has its flange 54 thermally shrunk upon the finished cylindrical surface 53 of the trap wall 10. The shrink fit of the flange 54 grips the top side plate member 55 firmly to the wall 10. The cylindrical surface 69 of the top side plate member 55 fits with a sliding fit in the inner cylindrical surface of the wall 64 to form a closure between the top side plate members and the peripheral cylindrical wall 64 to an adequate degree. This is in accordance with my prior Patent No. 2,244,397.

The throating through the cylindrical wall 64 which is herein specifically shown comprises two pairs of throats. Each pair comprises a main throat 70 (see Figures 1 and 2), and an auxiliary or priming throat 72. The main throat 70 in each case discharges through a gradually enlarging passageway into the separator above a horizontally extending wall 73 and the throat 72 and its expanding passageway extends down to the channel 74 formed in the lower outer annular trough in the bottom of the separator. The wall 73 extends only from the edge 75 (see Figure 1) to the edge 76 in the same figure for each pair of throats. Between these separate horizontal walls 73, the troughlike channel 74 opens clear up to the top of the separator chamber 9. The function of the walls 73 is to segregate the mixture discharged out of the throats 70 from the return flow of liquid substantially free of air back through the auxiliary throats

72 during the priming operation. The impeller is not shown in Figure 2, but it, if seated in the chamber 65, Figure 2, would rotate in a clockwise direction. The throat 70, which is the main throat, is anterior in direction of rotation to the priming or auxiliary throat 72, these two throats being placed closely adjacent each other, and the two pairs of throats being separated by a cylindrical wall which is swept by the ends of the blades 58 with substantially only mechanical clearance.

The rotor 6 consists of two functionally independent parts, although the two are joined mechanically together. The top part of the rotor is the main pumping impeller and the bottom part of the rotor provides the sealing channel. The rotor is made up of the two separate mechanical parts threaded together, namely, the upper member which has the annular plate 59 with a depending internally threaded flange 78 and sealing impeller blades 79. The bottom part of the rotor is formed of a disk 79 having a central hub 80 fitted and keyed upon the lower end of the shaft section 82. At its outer periphery, the disk 79 has an upwardly extending flange 83 which is threaded inside the threaded flange 78 to join the two rotor parts together. Between the disk 79 and the bottoms of the blades 78 which are formed on the lower surface of the annular plate 59 there is provided a narrow annular space in which is disposed the sealing disk 84 carried on the lower end of the sealing sleeve and disk member 5.

The disk member 84 has substantially only running clearance between the said blade 78 on the top, the rotor disk 79 on the bottom, and the flange 83 at its outer periphery. This running clearance is preferably of the order of $\frac{1}{4}$ ". The depth of the sealing blades 78 is of the order of $\frac{1}{4}$ " and may be more or less. This sealing disk 84 is carried on a cylindrical portion of the sleeve member 5 which is somewhat enlarged at 85 to receive the hub 80 of the rotor disk 79. The inner periphery 86 of the disk 59 which carries the main impeller blade 58 is spaced from the said enlargement 85 on the member 5 by a running clearance of the order of $\frac{1}{2}$ ", although this gap is not at all critical. Above the enlarged portion 85 of the sleeve member 5 the sleeve member fits relatively closely to the shaft section 82, but with a running clearance which may within practical limits be as large as desired to pass impurities. The sleeve member 5 has a shoulder which abuts against the lower end of the body sleeve 13 and at its upper end the member 5 is threaded to receive a nut which bears against the bottom surface of the neck 20, the said neck being hollow. The sealing sleeve member 5, within the body sleeve 13, is preferably slotted to provide additional storage space or standpipe space for sealing liquid, as will be described later, and the upper end of the sleeve fits about the shaft section 82 with a non-critical clearance which preferably is large enough to permit relatively free passage of entrained solids.

The neck member 20 has a drain opening into which is threaded a drain pipe 89 for draining off and returning by gravity to the source of liquid being pumped any outflowing sealing liquid. The drain pipe 89 is shown in the plane of the paper in Figure 1, whereas, preferably, it is disposed at right angles thereto, as indicated in its true position in Figure 2. The shaft section 82 has a shoulder 90 which serves as a

position of the rotor in the rotor chamber may be carefully adjusted. A bearing cover 117 is provided with an oil inlet pipe for lubricating the bearings 112 and 110, and bolts 118 clamp the cover 117 and bearing plate 115 upon the upper end of the said bearing barrel 4.

The pump is mounted upon a pedestal 3 as by means of a series of threaded plugs 119 preferably 3 in number, threaded into bosses 120 in the bottom wall 62. These plugs 119 in turn fit upon recessed bosses 122 on the pedestal member 3 and are clamped to the said pedestal member by means of cap screws 123 accessible through opening 124 in the said base member 3. Base member 3 may be bolted to a suitable foundation, or otherwise mounted. Obviously, the pump may be mounted by other means than the specific provision herein shown although the present is an advantageous arrangement in that through the three plugs 119 adjustment of the position of the pump may readily be made, and yet the pump securely attached to the base 3.

The rotor hub 80 is held against a shoulder on the shaft section 82 by means of a threaded cap member 125. The said cap member is perforated to receive a threaded draining plug 126. The hub of the rotating disk 79 is drilled to provide a drain opening 127, and this drain opening communicates with a radial port or passageway 128 leading to a bore formed in the lower end of the shaft section 82, the said bore 129 communicating with the inside of the cap 125. Thus, when it is desired to drain the pump, the liquid may be drained out of the pump body, which includes the separator and intake trap, by a suitable petcock or plug preferably introduced into the bottom wall 62. The rotor chamber and sleeve may be drained by removing the threaded hollow plug 67 which opens the bottom of the rotor chamber, and by then unscrewing the central plug 126 in the cap 125. This permits the seal and the sleeve member 5 to drain.

The pump is easily serviced. The clamping rings 48 and 49 may be released by unscrewing the bolts 50, and the top half of the pump, including the rotor, may then be lifted off and the rotor is thereby completely revealed.

The operation of the pump and its seal is as follows: Assume that the pump is provided with a suitable priming charge. Preferably liquid is retained to about the height of the gasket 47 in normal operation. With the pump elevated above the source of liquid and the suction connection 15 coupled to a suction pipe the lower end of which is submerged in the liquid to be pumped, and the discharge 40 connected to a suitable delivery point, the shaft 1 and rotor 6 may be rotated to start the operation of the pump to prime itself automatically and thereafter automatically discharge liquid.

The priming charge of liquid fills the lower part of the separator and fills the rotor chamber, including both the portion devoted to the main impeller and the portion devoted to the seal. Operation of the rotor drives liquid out of the impeller and throws all available liquid out of the bottom of the intake trap, discharging the same through all four of the throats shown in the present construction. It may here be noted that the throating, and the particular form of the impeller may be widely varied. The various forms of throats and impeller blades, including curved blades and involute type of casing with cutoff, and the various other known forms of throating and blading may be employed. However, in the

5 specific structure here shown, as soon as the liquid has been expelled from the impeller chamber, so that the rotor is unable to produce sufficient outward pressure to maintain an outward flow in all four of the throats, the liquid standing in the separator chamber 9 begins to flow back and quickly an organized circulation is established, consisting of the return of priming liquid through the auxiliary or priming throats 72 into the periphery of the impeller with discharge of mixture at the main throats 70 above the plate 73, such mixture breaking down into liquid and gas, the gas escaping upwardly, and the liquid tending to gravitate downwardly.

The whirling of liquid around the cylindrical wall of the separator chamber 9, tends also to squeeze the gas out of the mixture by centrifugal force, as is known in prior structures of self-priming pumps.

15 20 As soon as this circulation of priming liquid is established, air is removed from the intake side of the impeller, and thence the suction connection 15 is connected by the suction pipe to a source of liquid below the pump, or at a lower hydraulic head than the pump. The withdrawal of air by entrainment with the priming liquid and discharge of air into the separator decreases the gas pressure in the intake trap and intake passageways, or, in terms of the art, the pump begins 25 to exert a suction. This operation is also termed creating a dry vacuum.

30 35 The original priming charge has flooded the seal, and has filled all the interstices of the parts, including the space between the top plate 59 of the rotor, the top of the seal plate or disk 84, and the gap 130 between the sealing plate or disk 84 and the rotor disk 79 and the narrow gap providing communication around the outer periphery of the sealing disk 84. Depending upon the 40 hydraulic head, liquid tends also to stand in the gap between the sealing sleeve 5 and the shaft section 82.

45 50 Since the initial operation of the rotor drove all of the liquid out of the impeller chamber, and no liquid flows into the intake trap, and hence into the eye of the impeller, the seal must function on the liquid with which it started, and such liquid as was retained by the seal when the impeller 57 emptied itself. As the pump starts with assumed atmospheric pressure internally, the initial operation of the blades 78 on the rotor disk 59 exerts a pumping action upon the liquid therein contained, and tends to drive the same around the periphery of the stationary sealing disk 84 55 through the narrow gap 130 and up along the shaft section 82 into the reservoir formed by the open spaces within the body sleeve 13. Any excess which may be driven into these spaces will run out of the top of the sleeve member 5 and 60 into the bottom of the neck member 20, and out by way of the drain pipe 89 back to the source below the pump.

65 70 As the suction increases, atmospheric pressure working down upon the standpipe column of sealing liquid within the sleeve member 5 and the body sleeve 13 tends to push the sealing liquid back into the relatively wide space between the disk 59 of the rotor and the stationary sealing disk 84, whereupon, due to additional effective fluid medium or liquid medium a greater effective pumping pressure is developed by the blades 78. The seal is so designed with respect to the speed of rotation, the diameter of the sealing disk 84, and the effect of the blading 78 and the gap 130, 75 that, for the particular pump herein disclosed,

and for the principle herein illustrated, the pressure which may be developed by liquid standing at various radial positions within the blading 78, while yet maintaining a liquid seal in the gap 130, will cover the range of pressures from atmosphere to maximum practical suction.

Upon the suction being developed to a point where liquid is pulled up the suction pipe and over into the intake trap, the impeller 57 will be filled with liquid, and liquid pumping thereupon proceeds, the pump thereupon filling entirely with liquid, so long as liquid at the source covers the suction pipe. The leakage of air through the connections, or into the intake pipe, merely tends to restore the priming operation until such air or other gas is removed, whereupon liquid pumping again proceeds.

Assuming that the pump is now filled with liquid, the operation of the sealing disk is filled to maintain a seal against the entry of atmospheric or other gases along the shaft section 82. This is accomplished by the continued delivery of liquid into the sealing blades 78 to the gap between the inner periphery of the rotor disk 84 and the stationary sealing sleeve portion 85.

Since the pumping side of the seal is now continuously supplied with liquid by gravity, the blading 78 being thereby completely filled with liquid, maximum pumping pressure is developed, and, depending upon the wet vacuum then prevailing, a discharge of liquid occurs around the rim of the stationary sealing disk 84 through the narrow gap 130, and up along the shaft section 82 and out of the top of the sealing sleeve member 5 into the bottom of the neck member 20, and thence to the drain 98 and back to the source, or to waste if so desired. If the delivery pressure of the seal is equalled by the suction, no outflow of sealing liquid will occur. If clear liquid only is to be pumped, the seal may be designed to stop the outflow of liquid during liquid pumping against a predetermined suction head or a head in excess thereof. The permitted circulation keeps the seal constantly flushed with liquid and tends to wash out abrasive particles which may tend to lodge in these parts. The amount of flow thus occurring varies according to the suction exerted. It is to be observed in this connection that the pumping effect of the blades 78 in this type of structure needs to be only sufficient to develop the pressure difference of from atmosphere down to attainable vacuum preferably with a reasonable margin of safety. The point is that the maximum pressure which can be exerted to drive liquid up along the shaft section 82 and out of the top of the sleeve member 5 is no more than atmospheric pressure. Hence, the flow through the gap 130 and out through the gap between the shaft section 82 and the parts of the sleeve member 5 is relatively small and does not appreciably detract from efficiency of the pump.

By way of illustration, in a rotor of 5 inches diameter operating at 3450 R. P. M. with the sealing disk 84 of a diameter of $4\frac{1}{4}$ inches diameter, the blades 78 being of substantially $\frac{1}{4}$ " axial width, and being approximately 32 to 40 in number, and the gap 130 being of the order of from $\frac{1}{1000}$ " to $\frac{1}{16}$ ", I find that a pressure difference of 28 inches of mercury may be sustained. A series of tests shows that on a seal of the aforesaid dimensions, and in a range of speeds running from 3600 R. P. M. to 3030 R. P. M. the dry vacuum which the seal will maintain will range from 28.14 to 27.9 inches of mercury.

I have also found that for a speed of 1750 R. P. M. a sealing disk of about $7\frac{1}{2}$ inches diameter or slightly less will hold a vacuum of 27.5 inches. Obviously, the dimensions, speed and pressure differences may vary without departing from the principle and mode of operation herein disclosed. It is to be particularly noted that the seal is asymmetrical, in that a pumping action is definitely developed on one side, while on the other side the pumping effect is reduced or substantially eliminated, with the result that when both sides are provided with equal radial depth of sealing liquid, the liquid on the side where the pumping action is developed tends to migrate over to the side where minimum pumping action is developed. Hence, where a continuous supply of liquid is available on the pumping side of the seal, liquid tends to be passed through the seal on minimum pressure difference across the seal. However, as the pressure difference across the seal is increased, this flow diminishes, and may even be stopped, while a substantially frictionless liquid seal is maintained. The power absorbed in this liquid seal is relatively small, and since liquid is constantly passing through the pump and through the seal during normal liquid pumping, there is no tendency to overheat. Also during liquid priming, the walls of the seal are constantly cooled by the circulating priming liquid, and the seal will not overheat unless the main body of liquid overheats, in which event the pump could not develop a suction. In practice, this simply does not occur.

Liquid creeping up along the shaft 82, particularly above the standpipe or reservoir formed by the sleeves 13 and 5, encounters the radial shoulder 90 which operates as a slinger for throwing off any excess liquid. However, since a film may still creep upwardly, the second shoulder 96 is provided, and this at a greater diameter has an increased throwing tendency and clears off any film which would tend to ascend. As above explained, in order to make the pump tight against the escape of fumes or vapors, a yielding sealing ring 97 may be interposed between the sealing ring 90 and the oil retaining cup 99, and the oil retaining cup 99 may, through the overlap of the flanges 100 and 108, and the retention of a body of oil in the said cup 99, seal the passageway between these flanges against the passage of vapors through the narrow gap between the flanges 100 and 108. The trap 109 for the oil retaining cup 99 is employed to maintain the level of oil in the said cup 99 at a point where the flanges are sealed by oil. This special sealing of the parts may be omitted, except where explosionproof service is desired.

The pump may readily be drained as above explained as by a petcock in the wall 62 and by removing the threaded plug 87 and the plug 126 for draining the rotor chamber and connected passageway.

The principle involved in the seal of my invention is to create a higher mean angular velocity in the sealing liquid in the channel on one side of the disk than upon the other side. This principle holds good whether the disk be the rotating member or the channel be the rotating member. The blading on the moving part exerts a control of the liquid in the corresponding side of the channel to produce a high mean angular velocity. On the other side of the channel the stationary part exerts control of the liquid in that side of the channel to prevent, or avoid the production of, as high a mean angular velocity

of the liquid, and hence the kinetic effects of the liquids on the two sides is quite different.

The practical way of securing the difference is to put blades on the live member or rotating part on the side of the channel where pressure is to be developed and to bring the live or rotating part and the dead or stationary parts closely enough together to hinder the development of pressure on the side where sealing without development of pressure is desired. This difference may be observed upon opposite sides of the side wall of a closed impeller of a centrifugal pump. The side which carries blades develops pressure and the side next the side wall or side plate does not develop pressure. Obviously, where escape of liquid is permitted from the low pressure side there must be a provision for supplying liquid to the high pressure or pumping side.

It is not essential that the low pressure side of the seal be without blading for obviously blading might be disposed upon the stationary member on the low pressure side. The point is that the stationary part exerts sufficient hindrance to development of angular velocity that that side fails to develop a mean angular velocity as great as that developed upon the high side.

The clearances are not critical. No clearance less than normal impeller clearance need be provided in the seal or any connected part.

The angular velocity is effective in developing centrifugal effect in accordance with the square of the effective radius. Hence differences in radial depth of liquid in the channel are of little effect at the inner radius. But as the maximum radius is approached a small increment of increase or decrease represents a relatively great difference in effective development of pressure difference.

In Figure 9 I have shown a construction of seal in which pressure is developed throughout the entire or substantially the entire outer part of the radius of the high pressure side of the sealing channel whereas pressure is developed throughout only the inner part of the radial depth of the other side of the channel. Structurally this is accomplished in Figure 9 by providing blades 78 upon the bottom of the disk 59 for the outer part of the full radial distance to the periphery of the disk 84 just as in Figures 1, 5 and 6. However, instead of having the narrow gap 130 between the bottom disk 79 and the stationary sealing disk for the full radial distance as shown in Figures 1, 5 and 6, the disk 79a in Figure 9 carries blades 132 from the central part out to a point short of the full radial extent of the stationary sealing disk 84 leaving the short dead gap 130a at the outer margin of the said disk 84.

If the channel is full of liquid, the development of pressure by the blades 78 is as before. These blades produce a relatively high mean angular velocity throughout the entire outer radial extent of the disk 84 and thereby develop pressure which tends to discharge about the peripheral margin of the disk 84 over into the relatively dead space of the gap 130a where angular velocity of the sealing liquid is minimized. However, as soon as liquid enters blades 132 a counter pumping action is developed, and this tends to oppose an equal depth of liquid at the same radial distance on the upper or high pressure side. The result is that on lower pressure differences or suctions in the pump, other things being equal, the seal will discharge less sealing liquid than in the arrangement of Figure 1. On higher suctions, the seal is just as effective to withstand pressure differ-

ences, because as soon as the pressure difference is great enough to force the liquid of the seal beyond the ends of the blades 132, these blades no longer tend to exert an equalizing pressure, and the full asymmetrical effect of the seal of Figure 1 is produced. Hence this form of seal is just as effective to withstand the higher pressure differences corresponding to higher vacuums in the pump as that of Figure 1, but on low suctions the discharge of sealing liquid which occurs in the embodiment of Figure 1 is reduced in the embodiment of Figure 9.

The seals shown in both Figure 1 and Figure 9 are asymmetric seals, that is, they will resist the unsealing tendency of the atmospheric pressure tending to force liquid out of the channel and air into the intake or suction side of the impeller; but they do not provide the same resistance to unsealing in case the pressure difference be applied in the other direction. The seal of Figure 9, in addition to being asymmetric is self-compensating or self-balancing to the extent that the blades 132 plus the non-pressure developing gap 130a will develop as much, or substantially as much, pressure as will the top blades 78, and thereby not only resist unsealing but also reduce or wholly prevent the flow of liquid through the seal and into the sleeve. The pump with that form of seal (Figure 9) may be run without discharging any liquid through the outlet. Obviously, by variation of the effectiveness of the respective blades and gaps, balance or any desired degree of unbalance may be attained. The asymmetric seal may be employed for resisting any uni-directional pressure or asymmetrical pressure condition. The self-compensating or self-balancing form of Figure 9 may be employed where little or no runoff of sealing liquid is desired.

I do not intend to be limited to the details shown and described, as they are illustrative, and not intended to be limiting except as made essential by recital in the appended claims.

I claim:

1. In a self-priming pump having a vertical impeller shaft, a rotor including an impeller on said shaft, a casing providing an intake trap having an inlet, a rotor chamber, a separator having an outlet, throating between the separator and the chamber permitting the re-entry of priming liquid into the peripheral part of the impeller during priming, a stationary sleeve surrounding the shaft extending down through the intake trap and terminating at its lower end in a stationary disk, said rotor comprising a channelled seal ring closed at its outer periphery and having end walls above and below the margin of the disc, the lower end wall being attached to the shaft to form a driving connection between the shaft and the rotor, the upper end wall carrying the impeller blades cooperating with said throating, said upper end wall being annular, and having its inner periphery spaced from said sleeve by a narrow annular gap constituting a liquid inlet into the top of the sealing channel, and blade means carried on the inside of the upper annular wall of the channel tending to drive sealing liquid around the outer periphery of the disk, said bottom annular wall and the bottom of the margin of the disk being positioned so closely to each other along at least the outer margin of the disk that sealing liquid cannot develop sufficient centrifugal force therein to oppose an equal radial depth of sealing liquid within the pumping means on the upper side of the seal disk.

2. In a vertical pump a rotor, a shaft therefor, a stationary sleeve closely surrounding the shaft but not tight thereupon, a sealing disk carried on the lower end of the sleeve, said rotor comprising a movable disk secured to the shaft and lying close to the bottom wall of the sealing disk, a peripheral circular wall and an inwardly extending flange spaced a substantial distance from the top wall of the sealing disk, sealing liquid pumping means comprising vanes on the inner wall of the flange disposed closely adjacent to the top surface of the disk and upon being supplied with liquid acting to drive liquid toward the periphery of the sealing disk, said rotor carrying main impeller blades above said flange.

3. In a pump, a body casting comprising walls defining a central intake trap and a separator chamber, an intake connection communicating at its inner end with the trap and extending substantially horizontally, there being an opening in the top wall of said connection, a swingable back flow restricting valve having laterally extending hinge pins at its upper end, there being bearing seats for said pins in the side walls of said connection adjacent said opening, whereby the said valve may be inserted and withdrawn through said opening, a cover member for said opening and clamping means for said cover.

4. The combination of claim 3 wherein said cover member is domed, said cover member and said connection having a groove and a removable screen plate seated in said groove across the passageway through said connection.

5. In a pump a body casting having a top wall said top wall having a central opening and having an annular flange about said opening, extending inwardly from said top wall and a flanged annular bearing support extending upwardly externally of said top wall, a bearing barrel having a flange cooperating with the flange of said support, a removable sealing sleeve secured in said opening and clamped against said annular flange, a shaft having upper and lower bearings in said bearing barrel and extending through said second sleeve, an oil slinger carried by said shaft below said lower bearings, said slinger having a radially extending flange and an axially downwardly extending flange, an annular oil trap member disposed in said annular bearing support below the oil slinger, said oil trap member having a central upwardly extending annular flange disposed in telescopic relation with the axially extending flange of the oil slinger, an oil drain pipe extending laterally from the bottom of the oil trap member for draining away oil, and a sealing liquid drain channel below the oil drain pipe and opening into the lower end of the annular bearing support near the top of said sealing sleeve.

6. The combination of claim 5 wherein the shaft has a radial shoulder above the top of the second sleeve for slinging liquid creeping up the shaft.

7. The combination of claim 5 wherein the shaft has a radial shoulder above the top of the sealing sleeve for slinging liquid creeping up the shaft, and a second radial shoulder below the oil trap member, and a removable ring disposed in the annular bearing support between said shoulders, said ring fitting relatively closely to the shaft but being out of contact therewith, and being perforated for draining liquid down to the bottom of the neck.

8. The combination of claim 5 wherein the shaft has a radial shoulder above the top of the

70 sealing sleeve for slinging liquid creeping up the shaft, and a second radial shoulder below the oil trap member, and removable ring disposed in the annular bearing support between said shoulders, said ring fitting relatively closely to the shaft, but being out of contact therewith, and being perforated for draining liquid down to the bottom of the annular bearing support, and an annular yielding sealing ring between the oil trap member and the removable ring to prevent the escape of vapors, said oil drain member having a trap for retaining oil to form a liquid seal against the escape of vapors into the bearings.

9. In a pump, a main body casting comprising a top wall, three concentric cylindrical walls, the innermost walls defining a central sleeve, the top wall having a hole forming an extension of the bore of the sleeve, the upper ends of said three concentric walls joining the top wall, and the lower ends of said walls being faced off in approximately a common plane, a discharge connection opening through the top wall into the space between the outer wall and the intermediate wall, an integral hollow annular bearing support joined to the top wall and extending upwardly, said annular support being concentric with said sleeve and having a flange about its upper rim, and an intake connection extending upwardly over the top wall and opening into the space between the sleeve and the intermediate wall, said connection being integrally joined to said annular bearing support.

10. In a liquid seal pump, a vertical rotor shaft, a seal sleeve surrounding the shaft and carrying a stationary sealing disk, the rotor shaft extending through the sleeve and disk and carrying a rotor comprising a channel ring member open at the top and closed at the bottom and having a channel embracing the rim of the sealing disk and having blade means for developing a pumping action upon one side of the disk, the channel upon the opposite side of the disk communicating with the gap between the sleeve and the shaft, means providing a sealing liquid reservoir in communication with the said gap, and a liquid trapping chamber at the lower end of the sleeve and surrounding the channel ring member, said chamber trapping liquid in the channel ring member.

11. In a liquid seal pump, a rotor chamber having an inlet and having discharge throats, a vertical rotor shaft, a seal sleeve surrounding the shaft and spaced therefrom by a narrow gap, and carrying a stationary sealing disk within the rotor chamber, the rotor shaft extending down through the sleeve and disk and carrying a rotor comprising a channel ring member open at the top and closed at the bottom and having a channel embracing the rim of the sealing disk, and carrying on its top side open impeller blades cooperating with the throating, said channel ring member having on the upper side of the sealing disk vane means for developing a pumping action tending to drive liquid around the periphery of the sealing disk, the space upon the opposite side of the disk in said channel communicating with the gap between the sleeve and the shaft and comprising a narrow gap at the periphery of the disk, said gap being so narrow that no substantial pressure is developed by the liquid lying therein when the rotor is rotated.

12. Liquid seal comprising an interfitting annular channel member and a circular disk member and adapted to receive a body of sealing liquid in the channel in contact with the margins of the disk, said members being relatively rotatable,

means on the movable member comprising vanes for producing in the liquid on one side of the channel a relatively high mean angular velocity, and the surfaces of the members along the outer radial margin of the disk member on the other side of the channel promoting a relatively low mean angular velocity of the liquid in the corresponding portion of the channel, the movable member on the latter side of the channel having blades extending radially to a point short of the full radial extent of the disk member.

13. A self-priming centrifugal pump of the vertical shaft type having a body comprising an impeller and seal casing provided with an inlet opening and a discharge passageway, a separator chamber communicating with the discharge passageway and an inlet trap communicating with the inlet passageway, a vertically extending impeller shaft, an annular impeller in said casing, a centrally disposed sleeve extending through the inlet opening and through the annular impeller and carrying at its lower end a sealing disc, a sealing channel member embracing the disk and being carried by the shaft, said annular impeller being carried on said sealing channel member, the said casing being closed at the bottom to permit liquid being trapped therein.

14. A self-priming pump of the vertical shaft type having a body comprising an impeller casing with a central intake opening, an intake trap communicating with said opening, the casing having peripheral throating for discharge of fluid and reentry of priming liquid by operation of the impeller, a separator communicating with the throating, a vertical shaft extending down through the intake opening, an annular impeller surrounding the shaft and disposed in the casing, a sleeve surrounding the shaft and extending through the annular impeller, said sleeve being supported on the body at its upper end and bearing a sealing disc at its lower end, a channel member surrounding the disc, said channel member comprising an end plate at its lower side secured to the shaft and an annular plate at its upper side, the outer peripheries of the plates being coupled together, the impeller being supported on said channel member, said channel member providing a channel the upper leg of which communicates outside said sleeve member with the intake opening of the casing, the lower leg of the channel communicating inside the sleeve with atmosphere whereby the maximum difference of pressure to which the seal in the channel is subjected is full atmospheric pressure, said pump being adapted to trap a charge of priming liquid in the trap, casing and separator and to keep the impeller casing full when the rotor is not operating, said sleeve extending upward above the level of liquid trapped in the body of the pump whereby the charge of priming liquid will not escape when the rotor is not operating.

15. A self-priming centrifugal pump of the vertical shaft type having a generally circular pump body divided on a horizontal plane approximately midway of its height, the top part comprising inlet and discharge connections, a central sleeve, an annular trap wall and an exterior separator wall, the bottom part comprising an annular wall defining a central impeller and seal chamber, and an outer separator wall adapted to register with the separator wall of the top body part, there being an annular separator surrounded by the aforesaid exterior wall of both parts, a rotatable drum shaped sealing member

disposed in the lower end of the chamber, said sealing member having an internal sealing channel and bearing at its upper end an annular impeller, there being throating in the upper part of the chamber wall providing discharge and priming communication between the impeller and the separator, a sleeve extension secured to the sleeve of the top body portion and having a sealing disc embraced by said sealing channel, and a top plate member for the top side of said chamber coupled to the lower end of the trap wall, an impeller shaft journaled on the pump body and extending down through the sleeve and the sleeve extension and being connected to the sealing member, the pump body being adapted to trap and retain a charge of priming liquid in the chamber, trap and separator.

16. In a vertical self-priming pump of the class described having a body comprising a trap, a separator, and an impeller and sealing chamber, a drum shaped channel member providing a sealing channel and having a closed head on the bottom and a centrally apertured head at the top and carrying pump impeller blades disposed in the chamber, a sleeve extending downwardly from the top part of the body into the chamber and bearing a sealing disc disposed in the sealing channel, there being a top sealing gap between the disc and the upper head communicating through the aperture with the intake side of the impeller, and a bottom sealing gap between the disc and the bottom head of the member communicating with atmosphere through the sleeve, liquid seal blading carried by the apertured head, said blading extending from substantially the outer periphery of the channel inward to influence the fluid pressure in the top sealing gap to resist suction on the seal, the gap on the bottom of the disc consisting of an outer portion of small transverse dimensions designed to prevent development of pressure so that liquid will remain in contact with the periphery of the disc for sealing the same, and an inner portion lying radially inside the aforesaid outer portion for developing liquid pressure when the sealing liquid in the bottom gap extends radially inward beyond the outer portion of the bottom gap.

17. An asymmetrical self balancing liquid seal of the class described comprising a drum shaped channel member providing a sealing channel and having an outer imperforate head and an inner apertured annular head, a driving shaft connected to the imperforate head and extending through the annular head, a stationary sleeve surrounding the shaft and bearing a sealing disc embraced between the heads and lying in the channel, said disc being separated from said heads by a top gap and a bottom gap, blading on the inside of the annular head, said blading acting upon liquid in the gap to develop pressure tending to force liquid across the edge of the disc into the bottom gap, and blading on the inside of the bottom head of less maximum diameter than that of the blading on the annular head for developing pressure in the bottom gap only on liquid disposed on a less diameter than that upon which the upper blading develops pressure.

18. In a pump of the vertical shaft type, the combination of a pump body comprising an impeller and seal chamber having peripheral throating for the discharge of liquid and having a central inlet, a sleeve rigid with the body extending down into the chamber and bearing a sealing disc, a shaft disposed in the sleeve but out of contact therewith, shaft bearing means rigid with the

body of the pump and disposed above the end of the sleeve, a liquid drain chamber and an oil drain chamber both disposed between the top of the sleeve and the bearings, a sealing channel member having a channel embracing the margin of the disc, said member being carried on the shaft, and an impeller carried on the channel member and disposed in the chamber for cooperation with the throating and with the inlet, the top of the channel opening into the inlet and the bottom of the channel opening into the sleeve.

19. In a pump of the vertical shaft type, the combination of a pump body having an impeller and seal chamber, a sealing channel member having a closed lower plate and an annular upper plate joined at their peripheries to provide a channel, said member being disposed in the chamber, a sleeve member extending into the channel member and bearing a sealing disc the margin of which is embraced by the channel, an annular impeller carried on the member and loosely surrounding the sleeve, a vertical shaft extending through the sleeve and having bearings supporting the same out of contact with the sleeve, said shaft extending through the closed lower plate and being secured thereto, said shaft having a central drain passageway in its lower end communicating with the channel below the plate, a fastening nut on the lower end of the shaft for fastening said lower plate to the shaft, a plug for closing the lower end of the passageway, there being an opening in the bottom of the chamber through which access to the plug and to the nut may be had, and a closure plug for said opening.

20. A rotary liquid seal adapted to sustain a predetermined difference in pressure comprising a disk member and a rotatable channel member having a liquid holding channel embracing the outer margins of the disk member, but out of contact therewith, said channel member carrying pressure developing blades on the low pressure side of the seal, said blades lying at the outer periphery of the disk and being capable of developing a pressure in the liquid at the periphery of the disk on the said low pressure side of the seal great enough to force liquid over into the high pressure side of the channel against the predetermined difference in pressure far enough radially to form a complete liquid seal, said channel member having on the high pressure side only of the seal a non-pressure developing clearance

gap at the outer margin of the disk between the side of the disk and the adjacent side of the channel and having pressure developing blades lying radially inside said non-pressure developing clearance gap for developing pressure in the liquid of the seal on the high pressure side when the pressure difference upon the seal is substantially less than said predetermined value and the liquid is driven by the first set of blades from the high pressure side of the seal radially in on the low pressure side of the seal to the extent of entering the blades on the low pressure side.

21. In a rotary pump having a casing with an impeller shaft entering the casing, a liquid seal for the shaft subject to suction of the pump on one side and to atmosphere on the other, said seal comprising two relatively movable members, one of said members comprising a disk, the other comprising a channel extending around the periphery of the disk and overlying the margins of the disk, said seal being adapted to retain a ring of liquid in the channel in contact with the margins of the disk on both sides, there being pressure developing blades carried on the movable member, said blades extending radially out to substantially the periphery of the disk and being capable of developing a pressure in the sealing liquid at the periphery of the disk on the suction side of the seal high enough to force liquid around the margin of the disk against the full suction of the pump over into the high pressure side of the channel far enough radially to form a complete liquid seal, said channel and disk having at the outer margin of the disk on the high pressure side only of the seal a narrow radially extending non-pressure developing clearance gap between the side wall of the margin of the disk and the adjacent side wall of the channel, and the movable member carrying pressure developing blades radially inside said clearance gap for developing pressure in liquid of the seal on the atmospheric side when the pressure difference upon the seal is less than the full pressure difference between atmospheric and the suction which the pump is capable of exerting.

22. The liquid seal of claim 17 wherein that part of the bottom gap which lies radially outside the blading on the bottom head is of small axial extent to prevent the liquid therein from developing its own full centrifugal pressure.

HARRY E. LA BOUR.
